AIR CONDITIONER CABINET OR SIMILAR ARTICLE

John K. Wagner, Marengo, and Richard F. Sharp, Cedar Rapids, Iowa, assignors, by mesne assignments, to Amana Refrigeration, Inc., Middle Amana, Iowa, a corporation of Delaware

Filed July 8, 1964, Ser. No. 80,753

Term of patent 14 years

(Cl. D62—4)

Fig. 2

Fig. 3

Fig. 4

FIG. 1 is a perspective view of our design for an air conditioner cabinet or similar article;

FIG. 2 is a front elevational view;

FIG. 3 is a fragmentary side view; and

FIG. 4 is a fragmentary bottom view of our design for an air conditioner cabinet or similar article.

The dominant features of our design reside in the portions shown in full lines in the drawings.

We claim:

The ornamental design for an air conditioner cabinet or similar article, substantially as shown and described.
